FRANK O. WELLS AND DAVID B. MILLER, OF GREENFIELD, MASSACHUSETTS, AS-SIGNORS TO THE WELLS CORPORATION, OF GREENFIELD, MASSACHUSETTS, A CORPORATION OF MASSACHUSETTS.

THREAD-CUTTING DIE.

Application filed March 22, 1921. Serial No. 454,400.

To all whom it may concern:

Be it known that we, FRANK O. WELLS and DAVID B. MILLER, citizens of the United States, and residents of Greenfield, in the 5 county of Hampden and Commonwealth of Massachusetts, have invented certain new and useful Improvements in Thread-Cutting Dies, of which the following is a specification.

- 10 This invention relates to improvements in metal cutting tools, and more particularly to screw or thread cutting dies for forming a thread on the outside of a circular piece of material, as a rod, bolt, pipe, or the like.
- 15 An object of the invention is to provide a thread cutting tool in which a plurality of lands or prongs are provided having the thread forming teeth thereon, which are so constructed and arranged that the chips, 20 or removed metal, will be directly carried away from the thread during the cutting operation, thus preventing the tool and removed chips from injuring, or in any way destroying the efficiency of operation.
- 25 A further object is to provide a thread cutting die so constructed and arranged that there is no possibility of the tool springing or becoming distorted in a circular direction during the thread cutting operation.
- 30 In other words, the tool is made sufficiently rigid and non-elastic as to prevent springing or distortion. Heretofore it has been a common practice to mount a thread cutting die in suitably formed holders to avoid the 35 possibility of the lands of the die becoming distorted, either in a radial or circular direction.
- 40 A further object is to provide a die in which the cutting edges will operate so as to produce a shearing or drawing action, similar to the operation of a chisel or draw-shave knife when held at an angle to the line of motion in order that the material may be removed with the least possible 45 expenditure of power, and whereby not only is a better thread produced, but the thread forming tool, or die, will be capable of greater endurance or length of service before it is considered worn out.

- 50 Referring to the drawings:

Fig. 1 is a plan view showing the die in operation, and illustrating the manner in which the removed material leaves the work.

Fig. 2 is a perspective view showing the

die removed from the work and illustrating the construction of the prongs or lands.

Fig. 3 is an end view looking along the axial line and directly into the die. This view clearly illustrates the inclined or angular position of the lands, also the recessed portion directly back of the cutting teeth.

Fig. 4 is a sectional view on the line 4—4 of Fig. 3 looking in the direction of the arrows, showing the inclined position of the lands and chip receiving recess.

Referring to the drawings in detail: 1 designates the body part of the tool in the outer surface of which is formed the longitudinal channels or grooves 2 to receive a suitable holder, as a chuck; 3, 4, 5, and 6 designate the four thread cutting prongs or lands having the teeth 3', 4', 5', and 6' formed on their inner curved surfaces. Located and formed immediately in the rear, or at the ends of the cutting teeth, are the longitudinal recesses or depressions 7, in order to provide proper and sufficient clearance to prevent the apex or crown of the finished thread on the work 7' from being injured or roughened. In other words, the finished 80 thread will not drag on the cutting teeth of the prongs.

A further important feature of our improvement is the location of the advancing or cutting surfaces 8, 9, 10, and 11 of the 85 prongs 3, 4, 5, and 6, in a plane that stands at an angle to the axis of the tool. This construction has the effect of removing the material similar to a chisel or draw-shave knife when held at an angle to the line of motion. This angle may be shown by the dotted line 12 (see Fig. 4), which is a prolongation of the advancing or cutting edge of one of the prongs, indicated at 13. 14 designates in dotted lines a plane coinciding 95 with the surfaces 8, 9, 10, and 11, which passes through the axis of the die and work (see Fig. 3), whereby the advancing or cutting edges are in planes passing through the axial or center line of the die. It is, of course obvious that these planes may be arranged in advance or ahead of the center, depending upon the kind of material being operated upon. It will also be observed that the planes of the advancing surfaces 8, 9, 10, and 11 are inclined slightly rearwards in addition to the angle 13, similar to the manner of tipping the blade of a knife.

when removing a shaving or chip. These surfaces are inclined at an angle to the surface of the work on which a thread is being cut, and not at right angles thereto.

5 The die, therefore, removes the material indicated in Fig. 1 at 15, by means of advancing cutting planes or surfaces that stand in planes that are at an angle to the line of motion (see 13, Fig. 4), and also at 10 an angle to the work, as shown in Fig. 3, at 14.

It is to be understood that the prongs are made sufficiently rigid at their bases so as to prevent any spring or distortion in a 15 circular direction during the cutting operations. The rigid construction is indicated by the line 14'. In use the die is placed in a clamping chuck or holder device in order to guard against any undue distortion of the 20 prongs radially, and also to accurately adjust the diametral distance of the cutting teeth with relation to each other.

In operation the die may move or travel 25 in the direction of the arrow shown in Fig. 1, and the work is held stationary, or both the die and work may be rotated, as desired. The metal which is removed is carried directly outward and forward of the die, as shown, thus preventing the removed metal 30 or chips from coming into contact with the finished thread. The teeth at the advancing end serve to form the thread on the work, while those at the rear portion serve to accurately guide the cutting tool.

What we claim is:

1. A thread forming tool comprising a body portion having an opening therethrough, a plurality of tapered prongs each formed with thread forming teeth, and recessed portions immediately in the rear of 40 each of the teeth of the prongs.

2. A thread cutting die formed with a plurality of cutting teeth located on separate lands, each land being formed with a curved recessed part back of the cutting teeth to 45 provide a clearance space for the finished teeth, the plane of the advancing or cutting face being at an angle to the work upon which a thread is being cut.

3. As an article of manufacture, a thread forming die having non-resilient prongs with thread cutting teeth thereon, the advancing or cutting face of the prongs being arranged at an angle to the axis of the article, and also in a plane which is slightly 55 inclined rearwardly to the work.

4. A thread forming die comprising a one piece member having a plurality of prongs, each prong having a row of thread forming teeth that are arranged at an angle to the axis of the die, and each row having an arc-shaped recess which is located between the rear edges of the rows of teeth and the forward or advancing edges of the following row whereby the finished thread 60 will be free from chips, as described.
